UNITED STATES PATENT OFFICE

2,443,095

JAR CAP

James S. Conant, Glenn Dale, Md.

Application February 13, 1945, Serial No. 577,680

2 Claims. (Cl. 215—72)

1

This invention relates to covers or caps for jars or other containers, and more particularly containers for cosmetics used in toilet kits around vanities and the like, where the containers and other articles used not only are useful but are likewise attractive in appearance.

In applying cosmetics considerable time is consumed in removing and replacing the caps of the jars or containers and therefore it is not possible to use a number of preparations contained in the conventional jars or containers having caps which ordinarily screw on without consuming a substantial amount of time, it being desirable to perform certain routine operations in accordance with custom in completing the toilet.

It is an object of the invention to provide an attractive and ornamental cap or cover for a jar or other container which can be easily and simply removed and replaced without particular skill or the use of two hands, in order that the contents of the jars may be instantly available.

A further object of the invention is to provide a device of the above character of simple and inexpensive construction and which can be interchangeably used on a plurality of jars or containers so that when the contents of one jar is used the cap may be placed on another full jar.

A further object of the invention is to provide a cap or cover of attractive appearance which may be easily manipulated to afford access to the contents of the receptacle to which it is applied.

Further objects and advantages of the invention will be apparent from the following description taken in conjunction with the accompanying drawing, wherein:

Figure 1 is a perspective illustrating application of the invention to a container and employing a rubber hinge pintle;

Fig. 2, a side elevation with parts broken away showing parts in section;

Fig. 3, a fragmentary plan view of the top with a spring pintle in dotted lines;

Fig. 4, a perspective of the spring pintle; and

Fig. 5, a detail of the hinge.

Referring to the drawing, a jar 10 of conventional construction adapted to contain one of the many creams or substances employed in the preparation of the toilet is provided with a bead 11 separating the main body of the jar from its upper portion 12 provided with external threads 13.

An L-shaped ring 14 is provided with internal

2

threads 15 by means of which the ring is adapted to be threaded upon the top of the jar 10 and have its threads cooperate with the thread 13 of the jar.

5 The ring 14 is provided with spaced hinge members 16 having rearwardly opening pintle or pivot slots 17 with enlarged inner extremities 18. The ring 14 is provided at its front with a catch or latching element 19 for fastening 10 the cap 20 in closed position.

The cap is provided with a hinge portion 22 having a slot 23 opening toward the front of the cap, while the rear end of the slot is provided with an enlargement 24 corresponding in 15 size to the enlarged portions 18 of the hinge portions of the ring 14.

The cap is secured to the detachable ring 14 by means of a pintle 25 which is a deformable resilient member, a solid rubber strip being 20 shown as an example. The pintle or pivot member is preferably of a configuration corresponding to the configuration of the slots in the hinge members but is slightly larger than such slots, and when the parts are assembled, is compressed.

The ring member and the top or cap are assembled prior to their application to a jar. This can be easily accomplished by placing the cap in inverted position on a flat surface and stretching 30 the distortable member edgewise through the slot in the hinge portion of the cap. Thereupon the ring is placed in its normal position over the hinge portion of the top and moved until the distortable member is seated in the enlarged 35 sockets of the hinge portions of the ring.

When the members are assembled the openings of the slots in the cooperating hinge portions extend in the same direction and when the cap is closed the rubber member forming the pintle or 40 pivot member of the hinge is twisted or distorted so that when the catch 19 is released the lid or cap will fly open to expose the contents of the jar or other container.

The latch 19 is fixed and consequently to unlatch the cover or top the hinge must yield. Accordingly forward pressure on the cap will allow it to become disengaged so that under the influence of the twisting pedal the cap will be swung upwardly to its open position.

50 Instead of a rubber pivot member a pivot member of other material as, for example a spring 26 may be employed. This spring should be preferably of a configuration non-circular as, for example generally rectangular in cross-section in order to prevent its rotation in the hinge members.

as shown with the mid-portion of the same slightly larger than its extremities 27 which latter are preferably of solid construction.

In lieu of rubber or spring any resilient material or materials having the same general characteristics may be employed for the pivot member.

It will be obvious to those skilled in the art that various changes may be made in the invention without departing from the spirit and scope thereof and therefore the invention is not limited by that which is shown in the drawing and described in the specification but only as indicated in the appended claims.

What is claimed is:

1. A cap for a container having a fastening portion at its front, a supporting ring for said cap, cooperating interfitting slotted hinge portions on said cap and supporting ring, a latch on said supporting ring in substantially diametrically opposed relation to said hinge portions and a recess in said cap engageable therewith when in closed position, and a distortable pivot member connecting said hinge portions and being in its normal undistorted position when the front end of the cap is away from said latch so that when the cap is released from the latch it will move quickly from the latter; said hinge portions being constructed for relative movement so that a predetermined lateral movement of the cap relative to the supporting ring will release the cap so that its front end may fly away from the supporting ring.

2. For application to the threaded mouth of a jar, an internally threaded mounting ring having a latch at the forward side and spaced hinge portions at the rearward side, said hinge portions

comprising a pair of spaced rearwardly disposed slotted members, a jar cap of a size to enclose the threaded portion of the jar and be held in position by said latch, said cap having a hinge portion adapted to fit between the spaced hinge portions of said mounting ring, said hinge portion having a forwardly opening slot, and a pintle comprising spring means extending through and engaging the slots in said hinged portions and normally maintaining said cap in an elevated position and adapted to be distorted when the cap is closed, said hinge portions being constructed and arranged for relative movement so that a predetermined lateral movement of the cap relative to the mounting ring will release the cap to expose the interior of the jar.
